UNITED STATES PATENT OFFICE.

ROLAND S. TROGNER, OF AKRON, OHIO, ASSIGNOR TO THE GOODYEAR TIRE AND RUBBER COMPANY, OF AKRON, OHIO, A CORPORATION OF OHIO.

DESIGN FOR A TIRE.

57,953.

Specification for Design.

Patented May 17, 1921.

Application filed August 20, 1920. Serial No. 404,923. Term of patent 14 years.

To all whom it may concern:

Be it known that I, ROLAND S. TROGNER, a citizen of the United States, residing at Akron, in the county of Summit and State of Ohio, have invented a new, original, and ornamental Design for a Tire, of which the following is a specification, reference being had to the accompanying drawing, forming part thereof.

Figure 1 is a perspective view of a tire showing my new design; and

Fig. 2 is a transverse section on the line 2—2 of Fig. 1.

I claim:

The ornamental design for a tire as shown.

ROLAND S. TROGNER.
